UNITED STATES PATENT OFFICE.

LEO V. GELDER, OF OAKLAND, CALIFORNIA.

DESIGN FOR A PREHEATING-CHAMBER FOR DOMESTIC BOILERS.

58,023.

Specification for Design.

Patented May 31, 1921.

Application filed July 19, 1920. Serial No. 397,515. Term of patent 7 years.

To all whom it may concern:

Be it known that I, LEO V. GELDER, a citizen of the United States, residing at Oakland, in the county of Alameda and State of California, have invented a new, original, and ornamental Design for a Preheating-Chamber for Domestic Boilers, of which the following is a specification, reference being had to the accompanying drawing, forming part thereof.

Figure 1 is an end elevation of the preheater.

Fig. 2 is a side view of same.

Fig. 3 is a bottom plan view.

I claim:

The ornamental design for a preheating chamber for domestic boilers, as shown.

In testimony whereof I affix my signature.

LEO V. GELDER.
